LATCH MEANS FOR FOLDING OXFORD
EYEGLASSESVincent Tanasso, Harrison, and Jacob J.
Pomeranz, Brooklyn, N. Y.

Application April 23, 1935, Serial No. 17,804

5 Claims. (Cl. 88—44)

This invention relates, generally, to improvements in eyeglasses of the foldable type; and the invention has reference, more particularly, to improved latch means for releasably retaining such frames in folded condition.

This invention has for its principal object to provide a simple and yet durable and easily manipulated latch means for the purposes mentioned; the same comprising a minimum number of parts which can be economically produced and assembled.

The invention has for a further object to provide a novel construction latch means pivotally associated with the handle element of the frame of the eyeglasses, said latch means including means to aid in spacing the lenses and rims of the frame in spaced apart relation when these parts are folded together.

Other objects of this invention, not at this time more particularly enumerated, will appear in the following detailed description of the same.

Illustrative embodiments of this invention are shown in the accompanying drawing, in which:

25 Fig. 1 is an inside or rear face view of a foldable eyeglass frame having one form of the novel latch means according to this invention, the frame being shown in its open or unfolded condition; Fig. 2 is a fragmentary side edge elevation on an enlarged scale of the lens rims of the frame as folded together and held so related by the novel latch means; Fig. 3 is a fragmentary longitudinal section of the handle and latch bearing lens rim; Fig. 4 is a detail transverse vertical section, taken on line 4—4 in Fig. 3; Fig. 5 is a vertical longitudinal section through the parts as shown and disposed in Fig. 2; Fig. 6 is a fragmentary plan view of the rims about to move into folded and latched relation; and Fig. 7 is a horizontal section, taken on line 7—7 in Fig. 2.

Fig. 8 is a fragmentary plan view of a modified form of latch means according to this invention; Fig. 9 is a side end elevation of the same; and Fig. 10 is a vertical longitudinal section; said Figs. 9 and 10 showing the frame rims in folded and latched relation.

Similar characters of reference are employed in the above described views, to indicate corresponding parts.

Referring to the drawing, this invention is shown embodied in a pair of eyeglasses of the foldable or oxford type, comprising a pair of rims 1 and 2 to support the respective lenses 3 and 4. Connecting said rims between their

upper margins is a spring bridge 5, the same being joined at its respective ends to the respective rims by hinge connections comprising yokes 6 pivotally coupled by pintles 7 to abutments or knuckles 8, all as heretofore known with respect to folded eyeglass frames. Suitably mounted on opposed inner lateral portions of the rims 1 and 2 are nose-guard elements 9, as is customary.

One of the rims, as e. g. the rim 1, is provided on the outer lateral portion of its periphery 10 with a keeper element 10 having a notch 11, on at least one side of which, viz. the leading side thereof relative the folding movement of rim 1 toward rim 2, is provided an inclined shoulder or cam-portion 12, substantially tangent to the 15 rim periphery.

The other rim, as e. g. the rim 2, is provided on an outer lateral portion of its periphery with a finger-piece or handle 13, disposed substantially in the plane of said rim and adapted to project 20 radially therefrom. Mounted in connection with said finger-piece or handle 13 is the novel latch means which cooperates with the notched keeper element 10 of rim 1.

Formed in the finger-piece or handle 13, adja- 25 cent to the rim 2, is a cavity 14 to receive the pivoted end 15 of an upstanding latch element 16, and extending transversely through the handle body and across the cavity 14 is a pivot pin 17 upon which said end portion 15 of the 30 latch element is pivotally mounted for rocking movement toward and from the rim 2; the inner side of said end portion 15 being stopped against the rim periphery to thus determine its normal upstanding position. At its free end, said latch 35 element is provided with a thumb button or head 18. At its outer side, intermediate the pivoted end portion 15 and said thumb button or head 18, the latch element 16 is provided with an outwardly offset undercut shoulder 19 which 40 is opposed to the underlying portion of the cavity 14. Opening upwardly through the under- 45 face of said shoulder 19 into the body of the latch element is a spring-seat 20. Extending between the spring-seat 20 and the bottom of the cavity 14, outwardly of the pivoted end portion 15 of the latch element 16 is a coiled compression spring 21. The tension of this spring exerts an inwardly swinging thrust upon the latch element adapted to yieldingly hold the 50 same in its normal upstanding effective position. At its inner side, intermediate the pivoted end portion 15 and said thumb button or head 18, the latch element is inwardly cut away to form a supporting shoulder 22. Preferably the thumb 55

button or head 18 is provided with an inwardly projecting end portion 23 overhanging and spaced above said shoulder 22 to thereby form a laterally and inwardly open receiving notch 5 24 adapted to receive and embrace rim 1, when the latter is folded over rim 2. At least one side of said supporting shoulder 22, viz. the side toward which rim 1 moves when folded over rim 2, is downwardly and outwardly chamfered 10 to form an ascending inclined lift cam portion 25, which is engageable by rim 1 as it moves into folded relation to rim 2, whereby said rim 1 is caused to ride onto said shoulder 22 and be supported thereby in spaced relation to rim 2 15 when folded over the latter and secured by the latch element's effective engagement in the notch 11 of the keeper element 10. When the eyeglass frame is folded, the rim 1 is swung toward the rim 2 and over the rear face of the 20 latter, thus carrying the keeper element 10 of rim 1 toward the latch element 16 associated with rim 2. As rim 1 approaches completely folded position (see Fig. 6), the cam-portion 12 of the keeper element engages the latch element 25 16 which yields outwardly against its spring tension until the keeper notch 11 is aligned or registered therewith, whereupon the spring tension swings the latch element inwardly causing the same to enter said notch 11 (see Figs. 2, 5 30 and 7). As the rim 1 thus moves into folded and latched relation to rim 2, the lift cam portion 25 of the latch element also exercises its lifting effect upon the rim 1, so that when the locking operation is completed, the latter will be 35 fully engaged by the supporting shoulder 22, and thereby maintained in spaced relation to the underlying rim 2, whereby the lenses supported by the rims are also held spaced apart against rubbing contact one with another, and 40 consequently risk of scratching or other injury to the lens surfaces is avoided. This is of especial advantage when the lenses are of the toric type.

It is desirable to also provide means at the 45 inner lateral sides of the rims 1 and 2 to space such portions thereof apart when folded and latched as above described, and to also provide a stop means which will prevent the folded rim 1 from backing or shifting inwardly away from 50 the latch element as operatively engaged with the notched keeper element 10, whereby accidental release of the rims from secured folded relation might occur. The means for these purposes is substantially similar to the arrangement 55 and construction thereof disclosed and claimed in our co-pending application for United States Letters Patent Ser. No. 736,634, and comprises a spacer shoulder 26 which is affixed to the rear face of rim 2 at a point more or less 60 diametrically opposite the location of the latch element 16. This spacer shoulder 26 is provided, at the end thereof toward which rim 1 moves when swung to folded relation to rim 2, with an upwardly inclined lift cam 27 extending 65 between the rear face plane of rim 1 to the top of said spacer shoulder 26. Affixed to the outer side of said spacer shoulder 26, and having a free end portion projecting above the top of the latter, is a stop projection or lug 28 against 70 which the periphery of rim 1 is abutted when folded and latched relative to rim 2, thereby holding rim 1 from backing away from the latching means.

It will be obvious that the latch element may 75 be quickly and easily released by grasping the

finger-piece or handle 13 between the finger and thumb, and then by means of the thumb drawing outwardly against the thumb button or lead 18 to thereby swing outwardly the latch element 16 so that it is withdrawn from the notch 11 of keeper element 10, whereupon the stored tension of the spring bridge 5 will spread the rims 1 and 2 to open or unfolded condition ready for use.

It will be obvious from the above that a very simple and efficient latch means is provided 10 calculated not only to serve the desired function of locking the rims of the eyeglass frame in folded relation, but also functioning to space the folded rims and their lenses apart against rubbing or other contact one with another. 15 This novel and simple arrangement eliminates the necessity for employing additional, separate and bulky spacing projections or like means in affixed relation to the rims, thereby not only improving the appearance of the frames, but doing away 20 with the cost and work of producing and assembling such additional and separate parts.

The novel latch means within the scope and principles above set forth may be more or less varied in form and design. An example of such 25 variation is disclosed by the modified construction of latch means illustrated in Figs. 8 to 10 inclusive of the drawing. In this modified construction, the finger piece or handle 16' is provided with bearing ears 29 to support a trans- 30 verse hinge pin 30. The latch element comprises a body 31 formed at lower end with a transversely extending spacer shoulder 32 having, at least on the side thereof toward which rim 1 moves when folded over rim 2, an inclined 35 or tapered end portion 33 functioning as a lift cam portion. Projecting from the outer face of said spacer shoulder 32 are a pair of laterally spaced perforate knuckles 34 which pivotally engage the hinge pin 30. A torsional coil spring 40 35 engaged around the hinge pin 30 between said knuckles, and having its ends respectively engaging the finger-piece or handle 16' and said latch body, operates to yieldably hold the latch means in effective upstanding position. The 45 free end of the latch body 31 is provided with the thumb button or head 36 the inner end of which preferably overhangs and is spaced above the spacer shoulder 32, thus providing the laterally and inwardly open receiving notch 50 adapted to receive and embrace rim 1, when the latter is folded over rim 2. In the exercise of its latching and releasing functions as well as its function in spacing the rims, the modified latch means is manipulated and operates in a 55 manner substantially similar to that already above set forth in connection with the first described form of latch means.

Attention is called to the fact that, in both of the above described constructions, when the 60 notched form of keeper element is employed, and when the rim 1 is embraced between the overhanging end of the thumb button or head and spacer or supporting shoulder of the latch means, the rim 1, when in folded position, is 65 locked against any displacing movements in either direction horizontally sidewise of the latch means, and also against any displacing movements vertically of the latch means. In conjunction with such retention of rim 1 against 70 the enumerated displacing movements, the stop projection or lug 28 also holds the rim 1 against backing inwardly away from the latching means, and consequently the rims are retained against 75 all possible relative shifts which might tend to

accidentally release the same from the desired folded and locked condition.

Various changes other than those pointed out could be made in the novel latch means herein described and shown, and many apparently widely different embodiments of this invention could be made without departing from the scope thereof as defined in the following claims. It is therefore intended that all matter contained in the above description or shown in the accompanying drawing shall be interpreted as illustrative and not in a limiting sense.

We claim:

1. In folding eyeglasses having lens rims adapted to be normally urged apart by spring means, a notched keeper element on one rim, an upstanding latch means having its lower end portion pivotally associated with the other rim, spring means to yieldingly press said latch means toward the periphery of said last mentioned rim, said latch means being adapted to enter said notched keeper element when the first mentioned rim is folded over said last mentioned rim, a thumb button at the free end of said latch means, and the inner face of said latch means being indented between its pivoted lower end portion and its thumb button to provide a supporting shoulder upwardly offset from the plane of said last mentioned rim, said shoulder being adapted to underlie said first mentioned rim when so folded and latched thereby spacing the folded rims and their lenses apart.
2. In folding eyeglasses having lens rims adapted to be normally urged apart by spring means, a keeper element on one rim having a tapering portion substantially tangent to the rim periphery, a handle member rigidly connected with the periphery of the other rim, a latch means pivotally connected with said handle member, spring means to yieldingly press said latch means to upstanding relation to the periphery of said second mentioned rim and in the path of movement of said keeper element and its tapering portion when said first mentioned rim is folded relative to and over said second mentioned rim, and the inner side of said latch means being indented to provide a supporting shoulder to upwardly offset from the plane of said second mentioned rim, said shoulder being adapted to underlie said first mentioned rim when so folded and latched thereby spacing the folded rims and their lenses apart.
3. In folding eyeglasses having lens rims adapted to be normally urged apart by spring means, a notched keeper element on one rim having a tapering portion between the notch thereof and the rim periphery, a handle member rigidly connected with the periphery of the

other rim, a latch means pivotally connected with said handle member, spring means to yieldingly press said latch means to upstanding relation to the periphery of said second mentioned rim and in the path of movement of said keeper element and its tapering portion when said first mentioned rim is folded relative to and over said second mentioned rim, and the inner side of said latch means being indented to provide a supporting shoulder upwardly offset from the plane of said second mentioned rim, said shoulder being adapted to underlie said first mentioned rim when folded, said shoulder having a portion downwardly inclined to the plane of said second mentioned rim to lift the first mentioned rim onto said shoulder when the same is folded over said second mentioned rim.

4. In folding eyeglasses having lens rims adapted to be normally urged apart by spring means, a keeper element on one rim, a handle member extending from the periphery of the other rim, an upstanding latch means pivotally associated with said handle member, said latch means having an undercut shoulder portion at its outer side, spring means between said shoulder portion and said handle member adapted to yieldingly press said latch means to upstanding relation to the periphery of said last mentioned rim, said latch means being adapted to engage said keeper means when said first mentioned rim is folded over said second mentioned rim, and the inner side of said latch means being indented to provide a supporting shoulder to underlie said first mentioned rim when folded thereby spacing the folded rims apart.

5. In folding eyeglasses having lens rims adapted to be normally urged apart by spring means, a keeper element on one rim, a handle member extending from the periphery of the other rim, an upstanding latch means pivotally associated with said handle member, said latch means having an undercut shoulder portion at its outer side, spring means between said shoulder portion and said handle member adapted to yieldingly press said latch means to upstanding relation to the periphery of said last mentioned rim, said latch means being adapted to engage said keeper means when said first mentioned rim is folded over said second mentioned rim, and the inner side of said latch means being indented to provide a supporting shoulder to underlie said first mentioned rim when folded thereby spacing the folded rims and their lenses apart, said shoulder having an inclined lift cam portion to guide the latter rim onto the same.

VINCENT TANASSO.
JACOB J. POMERANZ. 60
